UNITED STATES PATENT OFFICE

ALEXANDER W. COPLAND, OF BIRMINGHAM, MICHIGAN

LAPPING MACHINE

Application filed January 17, 1927. Serial No. 161,641.

The primary object of my invention is to simultaneously cause a plurality of tools to describe independent circles relative to a plurality of work pieces, so as to simultaneously perform work thereon. Further, my invention encompasses the causing of each of a plurality of such tools to so operate upon each of a plurality of work pieces, whereby the inequalities of each of the tools may be averaged to produce a finished result which will be substantially perfect.

It is a further object of my invention to apply a rotary motion to a work or tool holder and cause the tools held thereby to describe independent circles so as to operate upon a plurality of work pieces at one and the same time.

Another object of my invention is to provide indexing mechanism which will shift the work holder or tool holder so as to cause different tools to operate on different ones of the plurality of pieces.

I have applied this invention to machinery for finishing tools in hardened metal accurately to size and shape by the lapping method. Hand lapping has been the usual practice where accuracy was necessary and when surface finish approximating a polish was desired, but the hand method is slow, and subject to human error, so that uniform size, finish and accuracy, as obtained by my method at slight cost, is not had.

The term "lapping" as used throughout the specification and claims is intended to mean, encompass and include the usual manner of lapping by use of an abrasive or polishing paste or compound, and is also intended to cover a polishing action without such abrasive or polishing medium, such as a burnishing operation, it being understood, however, that the novel mechanical movement hereinafter described and claimed is equally applicable to many other types of machines which have no relation to lapping or burnishing machines.

This invention more specifically deals with a machine that will produce the desired lapping motion simultaneously on a number of duplicate pieces, whereby a very high degree of accuracy can be obtained as well as duplication and uniformity of product. The duplicate pieces are mounted on a table at equally spaced intervals, with the laps carried in a head mechanism above the pieces. A circular motion is imparted to the laps by their carrier, and at predetermined intervals the table is lowered to disengage the laps from the work while an indexing mechanism spaces the table around one piece. When the table resumes the working position, each lap is working in another hole. A complete cycle of working operations of the machine produces the finished product, and this cycle of operations is automatic, reducing human supervision to a minimum.

With the above and other objects in view, my invention consists in the arrangement, combination and construction of the various elements of my improved device as described in the specification, claimed in my claims and shown in the accompanying drawings, in which:

Fig. 1 is a general view of the mechanism, partly in section.

Fig. 2 is a section taken on line 2-2 of Fig. 1.

Fig. 3 is a section taken on line 3-3 of Fig. 1.

Fig. 4 is a section taken on line 4-4 of Fig. 1.

Fig. 5 is an alternative arrangement of the lap carrier, showing gearing for rotating the laps.

Fig. 6 is an under view of Fig. 5 showing the gear arrangement.

Fig. 7 is a section taken on line 7-7 of Fig. 1.

Fig. 8 is an alternative table reciprocating cam.

In the drawings, 11 is the main frame or

casing of the entire machine. 12 represents an electric motor that supplies the main power for operating and rotating the lap carrier and work table, to be described later. 5 The motor 12 carries the sprocket 14 and through the chain 15 delivers power to the sprocket 16 on the shaft 17. The shaft 17 is supported in adequate bearings (not shown) and carries with it the bevel gear 18, the 10 spiral gear 19 and the cam 20. The bevel gear 18 meshes with and drives the bevel gear 21 at a suitable ratio and gear 21 therefore rotates the shaft 22 which is carried and supported in the bearing 23 attached to the frame casing 11 by the bolts 24. The collar 25 attached to the shaft 22 maintains its vertical location. On the upper end of the shaft 22 is another bevel pinion 26 which drives the bevel gear 27 on the shaft 28. Shaft 28 15 is also borne on suitable bearings and supported by suitable brackets from the main frame 11 (not shown). The shaft 28 carries the cam 29 which is so shaped that once each revolution of the shaft 28, the cam 29 pushes the roller 30 downward a distance determined by the height of the cam 29. The roller 30 is on a pin 31 carried on the rocker arm 32, and the rocker arm is trunnioned at 33 on the bracket 34 extending upward from the 20 main frame 11. On the end of the rocker arm 32, opposite the roller 30, is formed a fork 35 with suitable pins 36 engaging the yoke 38 in the slot 37 in the block 38. The yoke 38 is free to slide laterally in the slot 37 25 to allow for the eccentric motion of the block 38 relative to the fork 35.

It will be noted that rotation of the motor 12 finally imparts reciprocating motion at 30 stated intervals to the block 38 in a vertical direction, and it will be further noted that the gear ratios of the gears 18-21 and the gears 26-27 combined, determine the number of strokes of the block 38 per revolution of the shaft 17. Considerable latitude in 35 determining these ratios is present, and the ratio of the sprockets 14 and 16 permits a determination of the relative speeds of the motor 12 and shaft 17.

The spiral gear 19 mounted on the shaft 17 40 meshes with the spiral gear 39, and the construction of these gears is such that gear 19 has a single interrupted tooth that periodically engages a tooth in the gear 39 and moves it around its axis an amount corresponding to one tooth. The number of teeth in the gear 39 is determined in conjunction with the size of gears 44 and 45 so that the work carrier indexes as desired. The gear 39 is rigidly attached to the shaft 40 which in turn 45 is borne and supported in the brackets 41 and 42 projecting from the main frame casing 11. The collar 43 attached to the shaft 40 on one side of the bracket 42 and the gear 44 on the other side of the bracket 42 determine 50 the vertical location of the shaft 40 and its

associated parts. The gear 44 being fixed to the shaft 40, drives the gear 45 according to the relative number of teeth in the gears. The gear 45 is rigidly attached to the shaft 46 which in turn is borne in the brackets 47 and 49 projecting from the frame casing 11. The shoe block 48 with its smooth and hard lower surface is fitted over the lower end of the shaft 46 and fastened to it. The block 51 is fastened to the shaft 46 by the set screw 52 at a predetermined distance above the bracket 47. On the upper end of the shaft 46 is attached the work holder 50 which carries the pieces 53 which are to be lap finished. As shown in Fig. 3 a number of pieces are carried on the work holder 50, spaced at regular intervals on the circumference of a common circle 54.

Returning to the shaft 17 we find that the cam 20 rotates with it. The cam 20 is so constructed that it has one low spot in its circumference that is timed to allow the roller 55 to lift and hold just a moment before the interrupted tooth in the spiral gear 19 engages one of the teeth in the gear 39. Now, since the roller 55 is carried in the yoke 56 on the vertical push rod 57 which in turn is hinged at 58 to the end of the lever 59, and 59 is pivoted on the casing 11 at 60 and the other end of 59 has the ball head 61 resting in contact with the shoe block 48, it is evident that the downward weight of the shaft 46 and its associated parts will force the roller 55 into the notch in the cam 20, and the holder 50 will thereby lower by gravity an amount determined by the collar 51 which is sufficient to withdraw the work pieces 53 from the laps 62. While the work support 50 is in this lowered position, the interrupted tooth in the gear 19 engages a tooth in the gear 39 and indexes the shaft 40 around sufficiently to bring the laps 62 in registry with another work piece, whereupon the cam 20 at the proper moment pushes the roller 55 down again, thus lifting the shaft 46 and holder 50 back up into the working position as shown in Fig. 1. It will be noted that the face width of the gear 44 is sufficient to retain engagement with the mating gear 45 while the foregoing event occurs. It will also be evident that the choice of gear ratio between the gears 44 and 45 permits considerable latitude in setting up the machine for different kinds and quantities of work. The proportioning of the arm 59 also can be determined by the amount of table lift desired in conjunction with the height of the cam 20, and the collar 51 can be moved to a different spaced distance from the bearing stop 47 by means of the set screw 52. The space between the hub of the holder 50 and the bearing 49 is made sufficient to clear the maximum sized work piece.

Fig. 8 depicts an alternative cam 20a that can be substituted for cam 20 when work

pieces with cylindrical holes or surfaces are to be lapped. The cam 20a has a series of minor depressions 84 that impart a reciprocating motion to the work holder 50, while the one deep depression 85 permits the holder 50 to lower sufficiently to withdraw the laps from the work pieces for indexing in the same manner as the notch in the cam 20.

The auxiliary electric motor 13 is supported by bracket 64 from the frame casing 11 and to its armature shaft is connected the gear 65 which in turn meshes with the large gear 66. Gear 66 is attached to the hub 67 which in turn is journaled in the casing 11 at 15 68, the gear 66 resting on top of the casing 11 for support, and the collar 69 on the hub 67 giving vertical location. In the hub 67 is an eccentric hole that bears the vertical shaft 73 which is located vertically by its collar 76. The shaft 73 is free to rotate in its hole in the hub 67, and in the shaft 73 is a spiral key way or groove as at 74. Carried partly 20 on the hub 67 and partly on the body of the gear 66 is the sleeve 70 which is held in place by the bolts 71, thus rotating the sleeve 70 with the gear 66 but in a circular path whose center is eccentric to the gear 66 and concentric with the shaft 73. Within the sleeve 70 is the bushing 72 supplying a bearing surface 25 for the block 38. On the outer surface of the block 38 is a keyway parallel to the axis of the block, this keyway engaging the key or pin 75 carried by the sleeve 70. This permits the block 38 to move up and down but prevents relative rotation between the 30 block 38 and the sleeve 70. On the inner diameter of the block 38 is a pin or key which engages the spiral keyway 74 in the shaft 73. The combination of these keys and keyways 35 serves to advance or retard the angular relation of the shaft 73 to the sleeve 70 when the block 38 is moved up and down by forked rocker arm 35 previously described. Since the sleeve 70 is secured to the gear 66 and hub 40 67, the above described mechanism gives an intermittent rotative relation between shaft 73 and gear 66 although the shaft 73 is carried eccentric to the gear 66.

The work holder 50 previously mentioned, 45 in its upward movement stops on the underside of brackets 82 which project from the frame casing 11, and on the upper sides of these brackets 82 is borne the lap holder (or head) 78. Between the lap holder 78 and the frame casing 11 is interposed the ring plate 77. On either side of this ring plate 77 are attached the keys 79 and 80 at right angles to each other. In the casing 11 is a keyway 50 to match the key 79, and in the lap holder 78 is a keyway to match the key 80.

On the lower end of the shaft 73 is an eccentric crank pin 81 which passes through a clearance hole in the ring plate 77 and engages a bearing hole in the lap head 78. The 55 eccentric motion of the shaft 73 imparts an

eccentric motion to the crank pin 81, resultant motion of the lap head 78 being that of a small circle, yet not rotating on its own axis, to the restriction from the ring plate 77 and its keys 79 and 80. Thus, it follows that the 60 rotation of the gear 65, driven by the motor 13, imparts rotation to the gear 66 and its hub 67, and the shaft 73 journaled eccentrically in the hub 67 is moved about in a circular path so that the pin 81 on the shaft 73 also moves about in a circular path carrying with it the lap holder 78 with its laps 62 in the same circular path as the pin 81. However, the lap holder 78 is prevented from rotating on its own axis by virtue of the interposed 65 ring plate 77 with its keys 79 and 80. It follows that each and every point on the lap head or holder describes a small circle as shown in Fig. 3, and each lap 62 runs around this small circle within the work piece as 70 shown in Fig. 4.

The radius of the small circle just described is the distance between the center of the pin 81 and the axis of the hub 67 and the radius is variable since the shaft 73 is eccentric to the hub 67 and the pin 81 is eccentric to the shaft 73. The variation of this radius occurs when the block 38 is moved up and down, in the manner previously described, since such movement of the block 38 causes rotation of 75 the shaft 73 in its journal in the hub 67. Thus it will be seen a reduction of the radius reduces the diameter of the circular path of the laps 62 in the work pieces 53, causing the laps to withdraw from a groove as shown in the particular work pieces illustrated in Fig. 1. Such withdrawal of the laps removes any interference when the work holder 50 is lowered as previously described. The clamping or holding means for the pieces of work 53 have been omitted from the drawings for the sake of clearness, but it will be understood that the pieces of work are suitably clamped or held upon the work table 50 in any well-known and customary manner. 80

The variation of the radius of the working circle of the laps operates in another and very important manner as follows: If a work piece has high spots, one reason for lapping is to remove such high spots. In the construction illustrated and described, the balancing of the working parts is such that when a lap encounters a high spot, the lap tends to yield toward the center of its working circle and thus displaces the lap carrier 85 100 105 110 115 120 125 130 135 140 145 150 155 160 165 170 175 180 185 190 195 200 205 210 215 220 225 230 235 240 245 250 255 260 265 270 275 280 285 290 295 300 tricity and the working circle of the lap is resumed, and weight of the block 38 keeps the laps 62 constantly in pressure contact with the surfaces they arelapping. This action continues until the high spots are all rubbed off and true circles in all work pieces result.

It will be apparent that the laps tend to describe a perfect circular path, and because of the periodic indexing of the work holder, each lap is ultimately brought in working contact with each piece, and because of the law of averages, the pieces ultimately arrive at a degree of likeness and accuracy heretofore unknown.

Under certain conditions it is desirable to rotate the laps 62 on their own axes while the above described events and motions are occurring, without otherwise changing these motions. To accomplish this lap rotation, I have shown an alternative construction in Fig. 5. In this construction the crank pin 81a extending from the shaft 73a passes on through the lap holder 78a and is keyed to the large gear 83 by the key 84. Meshing with this large gear 83 are a series of smaller gears 85, one for each lap 62. The laps 62 are fastened to these gears 85 so that they rotate with them and the extension of the lap shanks, into the holder plate 78a, serves to properly locate the gears 85.

When this alternative construction is employed, the action is as follows. The shaft 73a is carried around by the hub 67 (which is rotated by the gear 66) in an eccentric path relative to the center of the gear 66. When considered relative to the frame 11, the shaft 73a is rotating on its own axis. Now, the lap head 78a is prevented from rotation relative to the frame casing 11, but the lap head 78a has a circular motion (previously described) and since the shaft 73a does rotate relative to the frame casing 11, it follows that the crank pin 81a rotates relative to the frame casing 11, the result being a rotation of the crank pin 81a relative to the lap head 78a. Since the gear 83 is keyed to the crank pin 81a, it follows that the gear 83 rotates relative to the lap head 78a and thereby causes the laps 62 to rotate on their own axes while their axes are describing the small circular path previously described.

It should be noted that the intermittent angular change of the shaft 73 relative to the gear 66 is passed along to this alternative construction without change in function.

It should also be noted that except for the alternative construction depicted in Fig. 5 it is entirely possible to reverse the positions of the work pieces 53 and the laps 62 whereupon none of the events, functions, or results would be disturbed. That is to say, the work, instead of the tool holder, may be moved to cause portions thereon to describe independent circles and I desire that this

reversibility be considered in construing the claims.

It should be evident that I have devised a new and useful mechanism in a very novel and simple manner. Obviously, changes may be made in detail, by one familiar with the art, without departing from the spirit of my invention; and it is my intention to cover by my claims such changes as may be reasonably included within the scope thereof.

What I claim is:

1. The combination of a tool holding element, a plurality of tools disposed in spaced relation on said holding element, means for rotating each of said tools and means for imparting a co-planar circular oscillation to said tool holding element so as to cause the tools to describe a plurality of spaced independent circles.

2. The combination of a tool holding element, a plurality of tools disposed in concentric equi-distant spaced relation on said tool holding element, means for rotating each of said tools, means for imparting a co-planar circular oscillation to said tool holding element so as to cause the tools to describe a plurality of spaced independent circles, a work support for holding a plurality of work pieces in position to be engaged respectively by said tools, means for relatively moving said tool holding element and work support for disengaging said tools from their respective pieces of work, means for relatively rotating said tool holding element and work support for bringing said tools into respective registry with pieces of work different from the pieces of work originally engaged thereby, and means for relatively moving said tool holding element and work support for engaging said tools with their respective new pieces of work.

3. In a device of the class described, a tool holding element, a plurality of tools held thereby and means for imparting a co-planar circular oscillation to said holder and causing each of said tools to describe an independent circle, each circle being in a different vertical plane while simultaneously rotating said tools on their own axes.

4. In a device of the class described, a tool holding element, a plurality of tools held thereby in equidistantly spaced concentric relation, a work holding element adapted to receive a plurality of work pieces having circular surfaces, means for imparting a co-planer circular oscillation to said tool holder and causing each of said tools to describe circles around the circular surfaces of the work pieces, and means simultaneously imparting individual rotation to each of said tools.

5. In a device of the class described, a tool holding element, a plurality of tools held thereby, a work holding element adapted to receive a plurality of work pieces having cir-

cular surfaces, and means for imparting a co-planar circular oscillation to said tool holder and causing each of said tools to describe circles around the circular surfaces 5 of the work pieces, means for individually rotating said tools while moving in circular oscillation, and means for moving the tool holder and work holder relative to each other to bring different tools into operable relation to the work pieces.

6. In a device of the class described, a tool holding element, a plurality of tools held thereby, a work holding element adapted to receive a plurality of work pieces having circular surfaces, means for imparting a co-planar circular oscillation to said tool holder and causing each of said tools to describe circles around the circular surfaces of the work pieces, and means for periodically moving 15 the work holder away from the tools, rotating the work holder to shift the said pieces into alinement with different of the tools, and moving the work holder back toward the tools.

20 7. In a device of the class described, a tool holding element, a plurality of tools held thereby, a work holding element adapted to receive a plurality of work pieces having circular surfaces, means for moving said holder 30 and causing each of said tools to describe a circle around the circular surface of a work piece, and means for periodically moving the work holder away from the tools, rotating the work holder to shift the said pieces into 35 alinement with different of the tools, and moving the work holder back toward the tools, said latter means comprising a support for the work holder, a drive shaft for the same having a gear thereon, a drive gear 40 meshing with the gear on the shaft, one of said gears having missing teeth, to cause only periodical rotation of the drive shaft, and a cam driven from a source of power and operably connected to said shaft for raising and 45 lowering it.

8. In a device of the class described, a tool holding element having a plurality of tools spaced in a circular formation thereon, a work holding element adapted to hold a plurality of work pieces spaced in a circular formation thereon, in operable alinement with said tools, means for imparting a co-planar circular oscillation to said tool holding element to impart independent circular motion 50 to its pieces, and means for moving said elements apart and for rotating one of them to cause different tools to operably aline with different work pieces.

55 9. In a device of the class described, a tool holding element having a plurality of tools thereon in equi-distantly spaced concentric relation, a work holding element adapted to hold a plurality of work pieces thereon, positioned to be operated on by the tools, means 60 for imparting a co-planar circular oscillation

to one of said elements to cause its pieces to describe independent circles on the pieces of the other element, and means for imparting individual rotation about their own respective axes to the pieces on one of said elements.

70 10. In a device of the class described, a tool holding element having a plurality of tools thereon, a work holding element adapted to hold a plurality of work pieces thereon, positioned to be operated on by the tools, means for moving one of said elements to cause its pieces to describe independent circles on the pieces of the other element and means for automatically varying the size of 80 circles described by said elements when a tool encounters an obstruction on a work piece.

75 11. In a device of the class described, a tool holding element having a plurality of tools thereon, a work holding element adapted to hold a plurality of work pieces thereon, positioned to be operated on by the tools, means for moving one of said elements to cause its pieces to describe independent circles on the pieces of the other element, means for moving one of said elements axially of 90 said circles and means for separating the elements to disengage the tools and work pieces.

95 12. In a device of the class described, a tool holding element having a plurality of tools thereon, a work holding element adapted to hold a plurality of work pieces thereon, positioned to be operated on by the tools, means for imparting a co-planar circular oscillation to one of said elements to cause its pieces to describe independent circles on the pieces of the other element and means for simultaneously rotating the tools and work 100 pieces relative to each other while maintaining them in engagement with each other.

105 13. In a device of the class described, a rotatable driving member having a shaft eccentrically mounted for independent rotation 110 therein, whereby rotation of the driving member effects movement of the shaft about a circle, a projection on the shaft eccentric there-to, a tool holder eccentrically connected to said projection, means for restricting movement of the tool holder imparted by movement of the driving member through said connection to that of a small circle which causes a plurality of points on the holder to describe independent circles and means for rotating said shaft at intervals to change the eccentricity of said projection and thereby change the circles described by the points on the tool holder.

115 14. In a device of the class described, a tool holding element, a plurality of tools held thereby, a work holding element adapted to receive a plurality of work pieces, means for moving said work holder and causing each 120 of said tools to describe a circle, and means

for periodically moving the work holder away from the tools, rotating the said holder to shift said pieces into registry with said tools, moving the holder back toward the tools, said latter means comprising a support for the work holder, a drive shaft for the same having a gear thereon, a drive gear meshing with the gear on the shaft, one of said gears having missing teeth to cause only periodical rotation of the drive shaft, and a cam driven from a source of power and operably connected to said shaft for raising and lowering it.

CERTIFICATE OF CORRECTION.

Patent No. 1,848,108.

Granted March 8, 1932, to

ALEXANDER W. COPLAND.

It is hereby certified that error appears in the printed specification of the above numbered patent requiring correction as follows: Page 3, line 68, after the word "axis," insert the word due; and that the said Letters Patent should be read with this correction therein that the same may conform to the record of the case in the Patent Office.

Signed and sealed this 26th day of April, A. D. 1932.

(Seal)

**M. J. Moore,
Acting Commissioner of Patents.**
